UNITED STATES PATENT OFFICE.

JOHN B. NAU, OF NEW YORK, N. Y.

REVERSING-VALVE FOR REGENERATIVE FURNACES.

No. 878,306.

Specification of Letters Patent.

Patented Feb. 4, 1908.

Application filed July 25, 1906. Serial No. 327,729.

To all whom it may concern:

Be it known that I, JOHN B. NAU, a citizen of the United States, residing at New York city, borough of Manhattan, in the county 5 of New York and State of New York, have invented new and useful Improvements in Reversing-Valves for Regenerative Furnaces, of which the following is a specification.

My invention relates to improvements in 10 reversing valve systems on regenerative furnaces of the same style, but not necessarily of the same principle, as those illustrated in my U. S. Patents No. 805024 of November 21, 1905, and No. 816813 of April 15, 1906.

The valves used in the valve system Patent No. 805024, whether of the design described in that very patent or whether of the design described in Patent No. 816813, are 20 such, that when the two valves reach the same level in their intermediate positions, both form simultaneous water-seals with their respective upper and lower valve seats, thereby effectively interrupting any communication between any of the flues landing in the valve casing, and preventing any loss of gas. With all the advantages that such a system presents, its use under normal conditions nevertheless has one great disadvantage, viz.: it never permits, when it is desired 30 for instance to cool off the furnace, to put both ends of the latter simultaneously in direct communication with the smoke-stack, without first placing the valves in their intermediate positions, and then emptying 35 the lower seal of its water, to allow the hot gases to pass from the furnace to the smoke-stack. This latter proceeding would naturally expose the lower empty or partly empty 40 water trough to the influence of red-hot gases and cause their rapid destruction.

The present design has for its purpose, 45 while maintaining intact or practically intact the advantages of the former system, to provide means that will allow the valves to be operated so, that at any moment the gas can be shut off and be kept shut off tightly on one hand, while on the other hand, both 50 ends of the furnace can be put and kept in direct communication with the smoke-stack.

In the drawings, Figure I is a vertical cross-section of the valve system; Fig. II is a section on line I—I of Fig. I; and Fig. III 55 a plan view on line II—II of Fig. I.

Similar letters refer to similar parts.

The valve system is inclosed within a

metal casing 1, set directly over and surrounding flue openings, of which 2 leads to the left-hand regenerator, 3 to the smoke flue, and 4 to the right-hand regenerator. 60

Casing 1 is divided into three compartments, of which the two lower ones 5, forming the valve chambers, are separated by a partition 6 in such a way, that each chamber 5 will inclose one regenerator and one smoke flue opening. Through their top partition each chamber 5 communicates by means of an opening 7 with the third compartment, the gas or air chamber 8. Each opening 7 is located directly opposite one of the smoke flue openings 3. Gas chamber 8 is provided in its roof or in any other convenient place with a gas inlet opening 9, and at its two ends with cleaning doors 34. Opening 9 may be controlled by a valve, if judged necessary. 75

Each valve chamber 5 is provided with a reversing valve 10, that, by means of one or more hollow or solid spindles 11, can be moved up and down between its upper valve-seat 12 and its lower valve-seat 13. The upper valve-seat 12, placed around and below opening 7, is made of a hollow-walled, water-cooled shell, open at both ends, receiving cooling water through pipe 32, and discharging it through pipe 33; but this shell may not 85 be water-cooled. The lower water-seal is formed by a water trough 13, surrounding smoke flue opening 3. The water troughs, surrounding smoke flue openings 3, may be independent of each other, but I prefer to use 90 one single water trough for the two openings, stretching under partition 6 from one valve-chamber to the other. In order to prevent the passage of gas from one chamber to the other, I provide under partition 6 a flange 35 95 reaching to a certain depth into the water below. So as to decrease the height of the valve system above the floor level, water trough 13 is laid below casing 1 in the brick-work in such a way, that its upper rim corresponds about with the floor level. 100

Reversing valve 10, of a circular shape as shown on the drawings, or of any other suitable one, is substantially formed of a partition 14, surrounded on its rim by a water trough 15, normally filled with water or other liquid to the level of the overflow 16. The vertical cross-section of the valve shows a circular trough narrowing downwards and terminated below by a circular flange 17, to which is bolted a removable iron ring 18, meant to receive the first impact of the flame, 110

thereby protecting the valve proper against deterioration and possible cracking. This ring can easily be replaced, when worn out. The depth of water trough 15 and height 5 of valve may be such, that when the valve is placed midway between its two seats, it will form simultaneous water-seals with both its upper and lower seats, or the valve may be too short to form in any position simultaneous 10 water-seals with both of its seats. In other respects the valve and its accessories, may be similar to the one described in my Patent No. 805024 of November 21, 1905 or similar to the one in U. S. Patent No. 816813 15 of April 3, 1906.

The top of each spindle 11 is screwed to a crosspiece 19, which by bolts 20 is fastened to another crosspiece 21, which latter receives each respectively one end of a cable or chain 20 22, running over a wheel 23, mounted on and supported by standards 24, placed on the charging floor or in any other suitable place. To one side of this wheel is attached a toothed gear or rather a toothed sector 25, actioned 25 on by means of a pinion 26 and a hand wheel or a crank 27. This forms the operating and regulating device of the valve system. Any other suitable regulating and operating device may be used. Cooling and sealing wa- 30 ter is supplied through pipes 28, discharging the water into funnels 29 resting on top of crosspieces 19, or otherwise conveniently fastened to upper ends of spindles 11. From the funnel the water runs through pipe- 35 stems 11 to troughs 15 of the valves, and through overflows 16 is carried off through discharge pipes 30, shown in dotted lines, and falls into lower water trough 13, from where it is evacuated to the outside through 40 overflow 31.

It will be seen on the drawings, that when the two valves are placed at the same level in their intermediate positions, they form both water-seals with their upper valve-seats, but 45 not with their lower ones, thereby effectively preventing gas from entering the furnace, and yet leaving below free communication between the regenerator flues and the smoke flues. With this arrangement of the valve 50 system the two ends of the furnace can be, with the ordinary operation of the valves, put in communication with the smoke-stack, without in any way emptying the lower water-seal of its water and without admitting any gas to the valve. Therein the valve 55 system differs essentially from the one described in my previous patents, and makes it possible to obtain the following other great advantages.

60 When starting the operations of the valves from their intermediate positions, one valve will move upward the same amount that the other one will move downward. Of course when this latter valve has reached its lowest 65 position, a sufficient passage will have been

established between itself and its upper valve-seat for the necessary amount of gas to enter the furnace. But meanwhile the other valve, being placed in its upper position, will have opened a much larger passage 70 for the products of combustion, to pass between the valve and its lower valve-seat on their way to the smoke-stack. Thus an excellent draft will always be assured, whatever the positions of the valves. 75

The peculiar construction and operation of the valves, and the ease with which each valve can be opened to any extent from no admission to full admission of gas, and the excellent condition of draft that nevertheless will exist at all times, make it possible to regulate the admission of gas to the furnace with the valve itself, instead of doing it with a valve, controlling opening 9, as is done in all other systems known to me. Hence, 80 when using the valve system with gas, the regulating valve with all its accessories, controlling opening 9, can be omitted, thereby cheapening the valve system and simplifying 85 its operation. 90

When using it with air, the whole gas chamber 8 with all its parts, such as gas inlet opening 9, cleaning doors 34, etc. can be omitted altogether. The outside air will then enter directly through that opening 7, 95 that, according to the position of the valves, is kept open, or it will be prevented from entering through any of the openings 7, in case both valves are in their intermediate 100 positions shown on the drawing. A similar arrangement could be obtained with the design illustrated in my Patent No. 805024 of November 21, 1905, although with that design the draft conditions, not being as favorable as in my present design, a regulating valve in opening 9 could hardly be 105 omitted, without injury to the good running of the furnace.

All or only part of the partitions and walls of the casing may be water-cooled. Partition 6 may be solid or it may be hollow and water-cooled or it may be built of bricks, or the two valve chambers may be entirely independent of each other, each surrounded 110 by its own partitions or walls. 115

I claim as my invention:

1. In a reversing valve system, the combination of two valve chambers, each valve chamber having an upper valve-seat, a lower valve-seat, and a valve, the two valves being 120 so connected together through their moving apparatus, that at one time one valve will make a seal with its upper seat only, while the other valve makes a seal with its lower seat only, and at another time both valves 125 will make simultaneously seals with their upper seats, leaving a free passage below between each valve and its lower valve seat.

2. In a reversing valve system, the combination of two valve chambers and one gas 130

chamber, each valve chamber having an upper valve-seat, a lower valve-seat, and a valve, the two valves being so connected together through their moving apparatus, 5 that at one time one valve will make a seal with its upper seat only, while the other valve makes a seal with its lower seat only, and at another time both valves will make simultaneously seals with their upper seats, 10 leaving a free passage below between each valve and its lower valve seat:

3. In a reversing valve system, the combination of two valve chambers, each valve chamber having an upper water-sealing valve seat, a lower water-sealing valve seat, and moving between its two seats, a valve, too short to make at one time water-seals with both its upper and lower seats, the two valves being so connected together through their 15 moving apparatus, that at one time one valve will make a seal with its upper seat only, while the other valve makes a seal with its lower seat only, and at another time both valves will make simultaneously seals with their 20 upper seats, leaving a free passage below between each valve and its lower valve seat.

4. In a reversing valve system, the combination of two valve chambers and one gas chamber, each valve chamber having an upper water-sealing valve seat, a lower water-sealing valve seat, and moving between its two seats, a valve, too short to make at one time water-seals with both its upper and lower seats, the two valves being so connected 30 together through their moving apparatus, that at one time one valve will make a seal with its upper seat only, while the other valve makes a seal with its lower seat only, and at another time both valves will make simultaneously seals with their upper seats, leaving a free passage below between each valve and its lower valve seat.

5. In a reversing valve system the combination of the two valves with their moving 45 apparatus, each valve being inclosed in a valve chamber having an upper valve seat and a lower valve seat, and both valves being so connected together by said moving apparatus, that at one time one valve will make a seal with its upper seat only, while the other valve will make a seal with its lower seat only, and at another time, both valves can be made to make simultaneously seals with their upper seats, leaving a free passage 50 below between each valve and its lower seat, said moving apparatus being composed of the two valve stems and a cable connecting said stems and a wheel over which runs the cable and a toothed sector and a pinion acting on said sector and means to operate said pinion and to place and maintain either one valve in any desired intermediate position, the position of the other valve remaining dependent on the position of the first one.

6. In a reversing valve system the combina-

tion of two valves with their moving apparatus, each valve being inclosed in a valve chamber having an upper seat and a lower valve seat, and both valves being so connected together by said moving apparatus, 70 that at one time one valve will make a seal with its upper seat only, while the other valve will make a seal with its lower seat only, and at another time, both valves can be made to make simultaneously seals with their upper seats, leaving a free passage below between each valve and its lower seat, said moving apparatus having means to place and maintain stationary either one valve in any desired intermediate position, 80 the position of the other valve remaining dependent on the position of the first one.

7. In a reversing valve system, the combination of two valves with their moving apparatus, each valve having a water-sealing 85 trough, and being inclosed within the confines of one single valve chamber, said valve chamber having an upper valve seat and a lower water trough valve seat, the valve moving between said two seats, said moving apparatus having means to place and maintain stationary either one valve in any desired position between its corresponding valve seats, the position of the other valve remaining dependent on the position of the 95 first one.

8. In a reversing valve system, the combination of two valve chambers, each valve chamber having an upper water-sealing valve seat, a lower water-sealing valve seat, and a valve, the two valves being so connected together through their moving apparatus, that at one time one valve will make a seal with its upper seat only, while the other valve will make a seal with its lower seat 100 only, and at another time, both valves will make simultaneously seals with their upper seats, leaving a free passage below between each valve and its lower valve seat, said two lower water-sealing valve seats having water 105 communication with each other.

9. In a reversing valve system, the combination of two valve chambers, each valve chamber having an upper valve seat, a lower valve seat and a valve moving between the 115 two seats, said valve having a transverse partition, a water trough around the rim of the partition with a cross section that gets narrower below and terminates into a vertical flange, an iron ring fastened around said 120 flange, and an overflow on the water trough.

In testimony whereof, I have signed my name to this specification in the presence of two subscribing witnesses, this 24th day of July 1906.

JOHN B. NAU.
